UNITED STATES PATENT OFFICE.

ANDREW T. BREWER, OF MINNEAPOLIS, MINNESOTA, ASSIGNOR OF ONE-HALF TO JAMES M. BOYD, JR., OF SAME PLACE.

COMBINATION FEED-WATER HEATER AND BOILER.

SPECIFICATION forming part of Letters Patent No. 478,395, dated July 5, 1892.

Application filed March 19, 1892. Serial No. 425,593. (No model.)

To all whom it may concern:

Be it known that I, ANDREW T. BREWER, a citizen of the United States, residing at Minneapolis, in the county of Hennepin and State 5 of Minnesota, have invented certain new and useful Improvements in a Combination Feed-Water Heater and Boiler; and I do hereby declare the following to be a full, clear, and exact description of the invention, such as will 10 enable others skilled in the art to which it app- pertains to make and use the same.

My invention relates to steam plants, and has for its object to provide an apparatus which can be interchangeably used either as 15 a feed-water heater for the main or primary boiler of the plant or as a temporary boiler to run the pump-engine for refilling the main boiler, when for any reason it may have become empty—as, for example, when cleaning 20 out the same.

As is well-known, steam plants are used in many localities where water-pressure from a main or head of water is unavailable. This is common in steam plants used both for running 25 a steam-engine or for heating purposes in connection with a series of radiators. In all such cases it is of course necessary to occasionally empty the boiler for cleaning the same. In that event it has hitherto, so far as 30 I am aware, been necessary to refill the main boiler by hand, which is of course a laborious and tedious operation. It is common, as is well known, to heat the feed-water for the main boiler by means of the exhaust-steam 35 from the main engine or radiators.

The object of my invention is to so construct this feed-water heater and its connections that it may be converted at will into a temporary boiler for supplying steam for running 40 the pump-engine long enough to refill the main boiler.

To this end I employ a receptacle which is divided off into suitable water and heat medium compartments or divisions for the circulation 45 of the water and the heat medium, and I provide valved inflow and outflow circulating-pipes to and from the water-division, the latter of which terminates in the boiler, and the former of which, in addition to its connection 50 with the pump, has a valved branch extending to the boiler, a fire-pot constituting one

element or compartment of the heat-medium division and provided with detachable means for closing its fuel and draft openings steam-tight, and an exhaust-steam-supply pipe from 55 the main engine or radiators delivering to the said heat-medium division. Preferably the receptacle is composed of concentric closed drums spaced apart from each other, the inner member of which is used as the water- 60 division and the outer member of which or the space between the two shells, together with the fire-pot located within and near the bottom of the inner drum, a series of heat-flues from the said fire-pot extending through 65 the water-division, and a down-current circulating-pipe for the exhaust-steam, receiving from near the top of the outside drum and delivering into the fire-pot, constitute the heat- 70 medium division. A valved live-steam pipe extends from the top of the water-division to the pump-engine, the connection with which may be common with that of the valved live- 75 steam pipe leading to the pump from the main engine. A fuel-door and a draft-register may be provided for use on the fire-pot when the 80 plugs are removed. Normally the device will act as a feed-water heater for the main boiler. When for any reason the main boiler is empty, it is only necessary to turn the valves and apply fuel in the fire-pot of the 85 receptacle before named, and steam may be generated therefrom to drive the pump-engine.

The apparatus is illustrated in the accompanying drawings.

Therein, like letters referring to like parts throughout, Figure 1 is a view, partly in front elevation and partly in vertical section, with some of the parts broken away, of my preferred apparatus. Fig. 2 is a view in elevation representing in diagram a part of the main boiler and engine of the plant. Fig. 3 is a vertical section through the fire-pot portion of the receptacle, and Fig. 4 is a horizontal section on the line X X' of Fig. 1.

A is the main or primary boiler, B the main engine, B' the live-steam-supply pipe to the same from the boiler A, C the pump, and C' the pump-engine, the said parts constituting 95 the main elements of an ordinary steam plant, wherein the live steam is used as motive power.

D and E are respectively the inner and outer closed drums, constituting the main compartments of the interchangeable feed-water heater and temporary boiler, the former constituting the water-division and the latter one compartment of the heat-medium division.

D¹, D², and D³ are the feed-water connections from the pump, of which the branch D² terminates in the drum D and the branch D³ in the main boiler. The branch D² is provided with a valve d and the branch D³ with a valve d'.

D⁴ is the outflow-pipe for the feed-water from the compartment D to the main boiler A, and is provided with a valve d².

F F' F² are the live-steam-supply pipes to the pump-engine C', of which the branch F leads from the main boiler A and the branch F² from the compartment D. The branch F is provided with valve f, the main pipe F' with the throttle-valve f', and the branch F² with the valve f².

E' is the fire-pot, located within and near the bottom of the inner drum D and separated therefrom by water-tight walls.

E² is a removable plug for closing the fuel-inlet, and E³ a corresponding plug for closing the draft-register opening of the same.

E⁴ is the grate, and E⁵ the ash space or box below the same.

E⁶ are hinge-lugs for the application of doors over the fuel and draft inlets of the fire-pot.

E⁷ is the exhaust-steam pipe from the engine B, tapping the outer drum E and delivering thereto near its bottom.

E⁸ is a down-current exhaust-steam pipe receiving from near the top of the said drum at a point diametrically opposite the inlet from the pipe E⁷ and delivering into the ash-box of the fire-pot.

E⁹ and E¹⁰ are respectively a hood and pipe formed continuous with the outer shell of the outer drum and constituting the outlet for the heat medium, delivering either into the open air or into a stack. (Not shown.)

E¹¹ are heat-flues in vertical arrangement within and extending through the inner drum D, having their inlet-openings or lower ends in the crown-plate of the fire-pot and their outlet-openings or discharge ends in the top plate of the inner drum.

G is a water-gage, G' and G² test-cocks, and H, H', H², H³, H⁴, H⁵, and H⁶ are blow-off connections, all of the ordinary construction.

The operation is obvious. Normally the feed and draft openings are closed by the plugs, as shown in Fig. 1. The live-steam connections to the pump are set for admission from the main boiler, the section F² being closed by the valve f², and the feed-water connections are set for a continuous flow from the pump through D², inner drum D, and the outflow-pipe D⁴, the cold-water section D³ from the pump to the main boiler being closed by the valve d'. With this arrangement of the connections the apparatus will simply

work as an exhaust-steam feed-water heater for the main boiler.

When it is desired to use the apparatus as a temporary boiler, the plugs E² and E³ are removed from the fire-pot and doors (not shown) substituted therefor. The section D² of the feed-pipe from the pump is closed and the section D³ opened. The section F of the live-steam pipe from the main boiler is closed and the section F² is opened. The outflow feed-water pipe D⁴ is also closed by the valve d². Fuel is then applied in the fire-pot E', and the live steam will be carried off by the section F² to the supply-pipe F' and be delivered to the pump-engine, driving the pump and delivering the water therefrom to the main boiler through the section D³ until the boiler is filled. The connections may then again be changed, the plugs restored to the fire-pot, and on starting the main engine B the apparatus will then again resume its normal action as a feed-water heater.

It will of course be understood that the operation would be the same if a set of steam-radiators were substituted instead of the main engine B. The convenience and value of such an apparatus as this for refilling the empty boiler of a single-boiler steam plant in localities where water-pressure from a main or a head is unavailable will be fully understood and appreciated by all persons having a practical knowledge of such steam plants. Boilers must be frequently emptied for cleaning and repairs. It is economical to use an exhaust-steam feed-water heater. My invention makes such a heater available at will for refilling the boiler.

It should be noted that the relative arrangement of the water and the exhaust-steam compartments afford a very efficient form of feed-water heater. The exhaust-steam conduits inclose and subdivide the water-compartment, thereby bringing a very large amount of radiating-surface into contact with relatively small columns of water.

What I claim, and desire to secure by Letters Patent of the United States, is as follows:

1. In a steam plant, an apparatus interchangeably usable as a feed-water heater or as a temporary boiler, comprising a receptacle divided into water and heat-medium compartments or divisions, valved inflow and outflow circulating-pipes to and from the water-division for the feed-water, a fire-pot constituting one element or compartment of the heat-medium division, suitable inlet and outlet openings for the heat medium, and an outflow live-steam pipe from the water-division to the feed-water pump, substantially as and for the purpose set forth.

2. In a steam plant, an apparatus interchangeably usable as an exhaust-steam feed-water heater or as a temporary boiler, comprising a receptacle divided into water and heat-medium divisions, valved inflow and outflow circulating-pipes for the feed-water, a fire-pot forming one compartment of the heat-

medium division, an inlet-pipe for exhaust steam to said heat-medium division, an outlet for the heat medium, an outflow live-steam pipe from the water-division to the feed-water 5 pump, and means for closing the fire-pot flue and draft-openings steam-tight when employing the apparatus as a feed-water heater, substantially as described.

3. In a steam plant, the combination, with 10 the primary or main boiler for supplying live steam to an engine or system of radiators, of a steam-pump, a receptacle having water and heat-medium divisions, direct and indirect valved feed-water connections from the pump 15 to the boiler, one branch of which is through the water-division of said receptacle, valved live-steam connections to the pump-engine, one branch of which is from the top of the water-division of the said receptacle, an exhaust-steam pipe delivering to the heat-medium division of said receptacle, and a fire-pot constituting one compartment of the said 20 heat-medium division and provided with removable plugs for closing its fuel and draft-

register openings steam-tight, substantially 25 as and for the purpose set forth.

4. The combination, with the receptacle composed of closed concentric drums, of a box or dome within the inner drum near the bottom of the same, flues from the said box passing through the inner drum, feed-water-circulating connections to and from the inner drum, an inlet exhaust-steam pipe delivering into the outer drum near its bottom, a circulating exhaust-steam pipe receiving from the 30 top of the outer drum at a point opposite the inlet-pipe and delivering into the said box or dome at the bottom of the inner drum, and an outlet-hood and discharge-pipe for the exhaust-steam or other heat medium extended 35 from the top of the drum, substantially as described.

In testimony whereof I affix my signature in presence of two witnesses.

ANDREW T. BREWER.
